UNITED STATES PATENT OFFICE.

EDMUND P. KINNE, OF ALLIANCE, OHIO, ASSIGNOR TO AMERICAN STEEL FOUNDRIES,
OF CHICAGO, ILLINOIS, A CORPORATION OF NEW JERSEY.

COUPLING-LOCK MECHANISM.

1,323,292.

Specification of Letters Patent.

Patented Dec. 2, 1919.

Application filed August 31, 1917. Serial No. 189,057.

To all whom it may concern:

Be it known that I, EDMUND P. KINNE, a citizen of the United States, and resident of Alliance, in the county of Stark and State 5 of Ohio, have invented certain new and useful Improvements in Coupling-Lock Mechanism, of which the following is a specification.

This invention relates to coupler mechanism, and more particularly to coupler lock operating means.

One object of the invention is to facilitate, in a simple and novel manner, the operation of coupler locks.

Another object is to make the operation of a coupler lock convertible.

And a further object is to provide a coupler lock mechanism adapted to meet the various requirements for successful commercial operation.

Generally speaking, these and other objects are accomplished by providing in coupler mechanism, the combination of a coupler lock, and means operating said lock from below and from above the coupler.

The invention is illustrated on the accompanying sheet of drawings, in which,

Figure 1 is a side elevation of a coupler shown in dotted and dash lines, showing the coupler lock operating means, for the most part, in full lines;

Fig. 2 is a similar view showing a guide lever forming a part of the coupler lock operating mechanism, and

Fig. 3 is a front elevation of the arrangement disclosed in Fig. 2.

The various novel features of the invention will be apparent from the following description and drawings, and will be particularly pointed out in the appended claims.

Referring to the figures of the drawings, it will be noted that I have provided a coupler having a head 10, to the forward portion of one side of which a coupler knuckle 11 is pivoted by means of a knuckle pin 12. This coupler is provided with a lock having the well-known function of locking the coupler knuckle in closed position whereby two or more cars may be operatively connected. The lock 13 is mounted for vertical movement in the head 10 and may be guided in any suitable manner.

This particular invention has to do mainly with means for operating the coupler lock.

By means of my invention it is possible to

operate the coupler lock from above and below the coupler proper. To operate the lock 13 from above, I have provided a top lifter 14 which passes downwardly through an opening 15 in the rear portion of the coupler head 10, the lower end of the top lifter having a hook 16 which engages a handle or portion 17 to be gripped by the hook 16, said handle 17 preferably being an integral part of the lock 13 and being looped at the top of the lock. The top lifter 14 is provided with an eye portion 18 which may be operatively connected to any suitable operating means for raising the top lifter 14 and thereby raising the lock 13 to permit or to cause the coupler knuckle 11 to be moved outwardly into an open position.

To operate the lock from below the coupler, I have provided a bottom lifter 19 which extends upwardly through an opening 20 in the lower rear portion of the head 10. At its upper end, this bottom lifter has a laterally extending portion 21 and a downwardly extending portion leading from the portion 21 to form a hook. The upper or hook end of the bottom lifter 19 is received in a recessed portion 23 in the upper rear part of the coupler lock 13, the upper portion of the extension 21 being engageable with the lowermost portion of the hook 16 of the top lifter 14. The recessed portion 23 of the lock has a shoulder portion 24 which cooperates with the downwardly extending portion 22 of the bottom lifter to prevent accidental withdrawal of the hook portion 21 of the bottom lifter from the recess 23.

In assembling the parts, the lock is first inserted through the front of the coupler, then the bottom lifter 19 is inserted through the opening 20 in the head and its hooked portion is placed within the recessed portion 23 of the lock, then the top lifter 14 is inserted through the head opening 15, the hook 16 of the top lifter then being placed around the handle 17 causing the hook portion of the bottom lifter to occupy and be locked in the lower portion of the recess, in which position it is prevented from accidental withdrawal from the lock. It is apparent from this arrangement that the lock 13 may be raised from the top of the coupler by raising the top lifter 14 and also that the lock 13 may be raised from the bottom of the coupler by raising the bottom lifter 19 which presses upwardly against 110

the hook 16 of the top lifter. It is seen, therefore, that the coupler lock may be operated from above or from below. In other words, the operating mechanism is convertible.

In Figs. 2 and 3 I have shown the bottom lifter as provided with a guide lever 25, one portion 26 of which is connected to the lower bifurcated portion 27 of the bottom lifter, 10 and the upper portion of which guide lever is pivotally connected to a bracket 28 extending from the lower rear portion of the coupler head 10. By means of this guide lever, the bottom lifter 19 will be caused to 15 travel in a given path when the same is operated to prevent any wedging which otherwise might occur.

It is apparent that there may be various modifications of the arrangement herein 20 particularly shown and described, and it is my intention to cover all such modifications which do not involve a departure from the spirit and scope of the invention as set forth in the following claims.

I claim:

1. In coupler mechanism, the combination of a lock having a recessed portion and a handle, a lift member engaging said handle, and another lift member operatively connected to the first one and locked within said 30 recessed portion.

2. In coupler mechanism, the combination of a coupler lock having a recessed portion and a handle, a member connected with said handle for actuating said lock, and another member a portion of which is located in said recess for actuating said lock, said second member being locked in said recessed portion by the first mentioned member.

3. In coupler mechanism, the combination of a coupler lock, and a plurality of actuating members connected to said lock, one of said members having a locking effect upon the other.

Signed at Alliance, State of Ohio, this 45
27th day of August, A. D. 1917.

EDMUND P. KINNE.
